ABSTRACT

An improved process for fusing a carbon electrode to an insulating spacer is provided for use in making a component for electric overvoltage arresters. The improved process involves heating an insulating spacer, a carbon electrode and a bonding composition used to fuse the electrode to the spacer in an inert atmosphere substantially free from oxygen until the bonding composition is liquefied, setting the position of the electrode in the insulating spacer while the bonding composition is in a liquid condition, and then allowing the bonding composition to harden so that the electrode is permanently secured within the spacer.

**METHOD FOR FUSING CARBON ELECTRODES AND
INSULATING SPACERS USED IN ELECTRIC
OVERVOLTAGE ARRESTERS**

BACKGROUND OF THE INVENTION

This invention relates to an improved process for making electric overvoltage arresters used to protect telephone and other electrical transmission lines from serious on-line voltage surges. More specifically, the invention concerns a method for fusing the carbon electrode and insulating spacer components of a spark gap type surge arrester to improve the in-service reliability of the resulting arresters assembled from such components.

Typically, spark gap type overvoltage or surge arresters are constructed from a pair of spacer electrodes, an insulating spacer or sleeve which surrounds one of the electrodes and a suitable housing to hold the electrodes in a spaced arrangement. The spark gap formed between the electrodes functions as a protective device for the transmission line connected to the arrester. Under normal conditions, the spark gap insulates the arrester from the line and prevents the flow of leakage current through the arrester. When a lightning strike or some other high voltage surge occurs in the line, however, the air gap between the electrodes momentarily breaks down, thus permitting the flow of surge current through the arrester to ground.

Consequently, it is desirable that overvoltage arresters have a high current carrying capability, closely controlled firing or breakdown voltages, firing voltages independent of environmental conditions, fast firing times, and a repeated surge capability or long life. This latter characteristic, namely, long life, is particularly important when an overvoltage arrester is intended for use in telephone line protective equipment where high reliability service is desired. One recurring problem existing in current overvoltage arresters, which employ a pair of spaced carbon electrodes and an insulating spacer which surrounds one of the electrodes and fixes the gap space between electrodes, is the frequent failure of such arrester units after relatively few firings. Of course, one explanation for these high instances of failure is the natural damaging effect of repeated firings on the arrester unit.

However, and in accordance with the present invention, it has been found that another cause for the relatively short lives of many arresters results from the processing steps taken in their manufacture. Specifically, high temperature processes are often used to fuse one of the pair of carbon electrodes to the insulating spacer. Since copper and other metallic impurities as well as carbon itself can slowly oxidize under such extreme conditions, the carbon particles in the electrode tend to loosen and give rise to the formation of a carbon dust on the electrode. Naturally, the presence of loose carbon particles on the fused electrode surface tends to reduce the gap between the spaced electrodes after assembly and causes arrester failures by short-circuit at low voltages and normal currents. Thus, this general loosening of the carbon electrode surface vastly reduces the useable life of the final arrester unit assembled from the electrode.

Accordingly, this invention provides improved manufacturing techniques to facilitate the fusing of carbon electrodes to insulating spacers, and at the same time, increase the service life and reliability of carbon electrode, spark gap type arresters made from the fused electrode-insulating spacer components. Until now, the general process used to fuse a carbon electrode to an insulating spacer was carried out by injecting a bonding composition into a suitable bond area between the electrode and the spacer, heating the electrode, spacer, and bonding composition in an air environment until the bonded composition was liquefied and then cooling the bonding components to solidify the bonding composition. The process of this invention, however, eliminates many of the difficulties experienced in prior fusing processes by permitting the fusing of the electrode and spacer to be carried out in an inert atmosphere substantially free from oxygen.

SUMMARY OF THE INVENTION

In accordance with the present invention, a process for fusing a carbon electrode to an insulating spacer is provided for use in making a component for electric overvoltage arresters. The fusing process of this invention in its broadest form involves: transmitting a hollow insulating spacer, inserting a carbon electrode into the hollowed portion of the spacer, injecting a measured amount of a bonding composition in the space 10 between the insulating spacer and the electrode, heating the spacer, electrode and bonding composition in an inert atmosphere substantially free from oxygen until the bonding composition is liquefied, setting the position of electrode in the insulating spacer while the bonding composition is in a liquid condition and allowing the bonding composition to harden so that the electrode is permanently secured within the insulating spacer.

By the process of this invention, a carbon electrode is fused with an insulating spacer without oxidizing or causing powder formation on the surface of the electrode. This invention, therefore, allows the fused carbon electrode and insulating spacer to be used as a highly reliable unit in electric overvoltage arresters, and still more advantageously, permits the construction of overvoltage arresters having a high repeated firing capability. Moreover, this invention overcomes the difficulty of electrode surface breakdown and surface oxidation and provides consistently uniform, satisfactory bonds between the insulating spacer and electrode by carrying out the fusing process in an inert, substantially oxygen-free environment, such as nitrogen or carbon dioxide or alternatively in a reducing atmosphere such as dissociated ammonia.

BRIEF DESCRIPTION OF THE DRAWINGS

FIG. 1 is a flow sheet showing in diagrammatic form a continuous process for fusing a carbon electrode and an insulating spacer.

FIG. 2 shows one form of the fused insulating spacer and carbon electrode produced by the process of this invention.

FIG. 3 shows an assembled electric overvoltage arrester, having as components thereof, the fused insulating spacer and carbon electrode made by the process of this invention.

DESCRIPTION OF THE PREFERRED IMBODIMENT

As shown in the flow diagram of FIG. 1, the first step in the process of this invention involves the transmission of hollow insulating spacer 10 onto a nesting measured to support the spacer. A vibratory type hopper feeder is normally used to automatically place a series of insulating spacers into a plurality of such nests, which rest on a rotatable dial table. Rotation of the dial table is automatically timed by an indexing type drive assembly which rotates the dial table as each insulating spacer is fed to a nest.

A carbon electrode 11 is next automatically fed to and placed in the insulating spacer supported by the dial table. The insertion of electrode 11 in spacer 10 is likewise timed to correspond with the rotation of the dial table by indexing drive assembly.

A measured quantity of bonding composition is then deposited or injected into the appropriate space 13 between the electrode and insulating spacer. Although various bonding compositions can be used in the practice of this invention, a granular lead borate composition is preferred because of the consistently high strength bonds it forms between the carbon electrode and insulating spacer. It is understood, however, that any thermosetting or thermoplastic resin or other bonding composition which satisfactorily fuses the electrode and spacer and which does not otherwise interfere with the operation of the electric overvoltage arrester is suitable for use in the practice of this invention.

Next the assembled insulating spacer, electrode and bonding composition are moved into a heating chamber by the rotating dial table. Typically, radio frequency induction heating coils are used to heat the assembly to temperatures suffi-

cient to liquefy the bonding composition. When a granular lead borate bonding composition is used, temperatures in the range of about 1,000° to 1,500° F are required to liquefy the lead borate. During the heating operation, the atmosphere in the heating chamber is maintained in a substantially oxygen free state so that neither the carbon nor the metallic impurities in the electrode can oxidize. Although any inert atmosphere substantially free from oxygen can be used in the practice of this invention, nitrogen is preferred because of its relatively low cost and ready availability. Other inert gases of a type not readily ionized in an R. F. field may also be used in the practice of this invention.

After the heat treatment of the insulating spacer, electrode and bonding composition in an inert atmosphere, the position of the electrode in the spacer is set while the bonding composition is in a liquefied condition. By carefully setting the position of the electrode in the insulating spacer, a suitable air gap 21 is defined between the electrode 11 and electrode 15 in the finished electric overvoltage arrester 16. Typically, the air gap is automatically set by the combined action of a spring-loaded plunger, which is seated over the top of spacer 10 and electrode 11, and gap pins located in the dial table, which are forced up against the carbon electrode. Of course, the entire gap setting operation is carried out while the bonding composition is in a liquefied state.

Finally, after the gap setting operation is completed, the fused electrode and spacer assembly preferably are first cooled and then removed from the heating chamber and transported around the dial table for a sufficient time to allow the assembly to further cool so that the bonding composition can fully solidify. When the fusing operation is completed, the finished electrode and spacer are ejected into a collecting device and subsequently assembled into the finished arrester unit.

In the practice of the preferred process of this invention, the carbon electrode fused to the insulating spacer is a cylindrical rod-shaped electrode which has a plurality of grooves cut in the one its base surface which faces the disc electrode 15; disc electrode 15, likewise is provided with grid pattern of grooves 17 on its opposed base surfaces. In addition, the insulating spacer normally used in the arrester is a bored ceramic sleeve, which surrounds the cylindrical electrode. Since the upper surface 19 of the bored ceramic sleeve bears against the lower surface of the disc electrode in the finished arrester, the posi-

tioning of the cylindrical electrode in the sleeve defines the air gap 21 between the cylindrical and disc electrodes. When the fusing operation is carried out in air with a lead borate bonding composition at temperatures of about 1,000° F to 1,500° F, the cylindrical electrode surface is left with loose, unbonded particles which readily deteriorate during subsequent assembly operations. In particular, the grooved pattern on the base surface of the cylindrical electrode has a tendency to become loose and easily broken during assembly. However, cylindrical electrodes fused under the same conditions in inert nitrogen or carbon dioxide environments have strong surfaces, which are not easily abraded during subsequent arrester assembly steps, and, therefore, the carbon electrode surface pattern is neither loosened nor broken. Accordingly, the service life of arresters using the fused electrode spacer components prepared by the process of this invention have a much better repeated surge capability and longer life than arresters which used components fused in an air environment.

I claim:

- 20 1. In the process for fusing a first carbon electrode with a hollow insulating ceramic spacer carrying said first electrode in making a component for an electric overvoltage arrester having a second electrode and an air gap between said first and said second electrodes in said arrester's assembled form
- 25 by transmitting said insulating spacer to a nesting means for supporting said spacer, inserting said first electrode into said insulating spacer, and injecting a measured amount of a bonding composition between said insulating spacer and said electrode, the improvement comprising heating the insulating ceramic spacer and the first carbon electrode in an inert atmosphere substantially free from oxygen until said bonding composition is liquefied, determining said air gap by setting the position of said first electrode in said spacer while the bonding composition is in a liquid condition, and allowing said bonding composition to harden so as to permanently secure said first electrode within said insulating spacer.
- 30 2. The process of claim 1 wherein said insulating spacer carrying said first electrode is heated in a nitrogen atmosphere.
- 35 3. The process of claim 1 wherein said insulating spacer carrying said first electrode is heated in an carbon dioxide atmosphere.
- 40 4. The process of claim 1 wherein said bonding composition is lead borate.
